US00D773467S

(12) **United States Design Patent** (10) **Patent No.:** **US D773,467 S**
(45) **Date of Patent:** **** Dec. 6, 2016**

(54) **MEMORY CARD**

(71) Applicant: **SAMSUNG ELECTRONICS CO., LTD.**, Suwon-si (KR)

(72) Inventor: **Hee-Chang Cho**, Seoul (KR)

(73) Assignee: **SAMSUNG ELECTRONICS CO., LTD.**, Suwon-si (KR)

(**) Term: **15 Years**

(21) Appl. No.: **29/546,150**

(22) Filed: **Nov. 19, 2015**

(30) **Foreign Application Priority Data**

Nov. 12, 2015 (KR) 30-2015-0057079
